IVAN ORNBERG, OF DETROIT, MICHIGAN, ASSIGNOR TO HUPP MOTOR CAR CORPORATION, OF DETROIT, MICHIGAN, A CORPORATION OF VIRGINIA

SUPPORTING BRACKET

Application filed March 25, 1929. Serial No. 349,860.

This invention relates generally to brackets and has particular reference to supporting brackets adapted to be secured to vehicles.

While the supporting bracket hereinafter described is capable of many and diversified uses, nevertheless, it finds particular utility when used in connection with motor vehicles for rigidly securing the muffler outlet pipes therefor in position.

To this end the invention consists in the provision of a supporting bracket having means for clamping the muffler outlet pipe thereto without the use of bolts or other separable clamping devices, thereby cheapening the cost of production as well as expediting the assembling operation.

Other objects, advantages and novel features of construction of this invention will be made more apparent as this description proceeds, especially when considered in connection with the accompanying drawings wherein:

Figure 1 is a fragmentary side elevational view of a vehicle chassis having a bracket constructed in accordance with this invention secured thereto;

Figure 2 is a top plan view of the bracket prior to being assembled upon the chassis;

Figure 3 is a side elevational view of the construction shown in Figure 2;

Figure 4 is a sectional view taken on the plane indicated by the line 4—4 of Figure 2.

Referring now to the drawings it will be noted that there is fragmentarily illustrated in Figure 1 the rear end of a vehicle frame 10 having a cross rail 11 provided with laterally extending flanges 12 and 13 secured to the frame 10 in any suitable manner. Disposed beneath the frame 10 in accordance with the usual practice is a suitable exhaust outlet pipe 14 having its forward end connected to a conventional muffler diagrammatically illustrated by the character 15.

In order to provide an efficient construction the exhaust outlet pipe 14 is rigidly connected to the frame 10 by means of a bracket 16 which may be inexpensively developed from sheet metal. The bracket 16 is provided with a body portion 17 terminating at its upper end in a laterally projecting attaching flange

18 and having an opening 19 therein adjacent its lower end for receiving the pipe 14. The flange 18 is secured to the flange 13 of the rail 11 by means of a suitable fastener element 20 having a shank portion 21 extending through aligned apertures formed in the flanges 13 and 18 of the rail and bracket respectively. As shown in Figure 2 of the drawings the flange 18 preferably curves downwardly from the flange 13 so that when it is clamped to the latter by means of the fastener element 20, as illustrated in Figure 1, it will exert a tension upon the element and prevent the same from working loose.

The body portion 17 of the bracket terminates at the lower end in an extension 22 having an intermediate portion 23 bowed outwardly from the plane of the extension forming a projection 24 constituting a part of one side of the opening 19. Extending transversely of the extension slightly above the projection 24 is a pair of aligned grooves 25 having the inner ends thereof projecting into the opening 19. The arrangement is such that when the pipe 14 is in assembled position with the bracket the extension 22 is bent laterally upon the pipe forcing the latter into clamping engagement with the upper wall 26 of the opening 19. Incidentally, when the extension 22 is bent into the position illustrated in Figure 1, the projection bites into the surface of the pipe and prevents the same from movement relative to the bracket.

Thus from the foregoing it will be apparent that I have provided a simple and relatively inexpensive bracket capable of being expeditiously installed upon a vehicle for rigidly securing the muffler outlet pipe thereto. It will further be noted that the bracket illustrated herein may be readily clamped to the pipe by merely bending a portion thereof laterally into engagement with the pipe, thereby eliminating bolts and other forms of clamping devices.

While the invention has been shown and described in connection with a vehicle for connecting the muffler outlet pipe thereto it will be apparent that the invention is broader than this in its scope and may be employed with equal facility for connecting various

members to a support. Therefore, reservation is made to make such changes in the details of construction as may come within the purview of the accompanying claims.

5. What I claim as my invention is:

1. In combination, a bracket having an opening therein, a member having a portion extending into said opening, an extension upon the bracket forming one side of said opening and adapted to be bent laterally, and a projection on the extension operable upon bending the latter to move into biting engagement with the member.

15. In combination, a supporting member, a bracket having a laterally extending attaching flange engageable with said supporting member, and a fastener element for clamping said flange to the member, said flange being normally bowed relative to the supporting member and operable in its clamped position to exert a tension upon the fastening element to prevent loosening of the latter.

25. In combination, a bracket having an opening therethrough intermediate the ends thereof, a member having a portion extending through the opening, and means upon the bracket permitting a portion thereof forming one side of the opening to be bent laterally into clamping engagement with the member.

35. In combination, a bracket having an opening therethrough, a member having a portion extending through the opening, said bracket having a portion to one side of the opening adapted to be bent laterally to a position adjacent the member, and a projection on the bracket operable upon bending the portion aforesaid to engage the member and rigidly clamp the same to the bracket.

40. 5. In combination, a bracket having an opening therethrough intermediate the ends thereof, a member having a portion extending through the opening, said bracket having a groove therein permitting a portion thereof to be bent laterally into clamping engagement with the member.

45. 6. In combination, a bracket having an opening therethrough intermediate the ends thereof, a member having a portion extending through the opening, said bracket having a transversely extending groove therein adjacent one end thereof permitting the end portion aforesaid to be bent laterally to a position adjacent the member and means upon the bracket operable upon bending the said end portion of the bracket to engage the member and rigidly clamp the same to the bracket.

55. 7. In combination, a bracket having an opening therethrough intermediate the ends thereof, a member having a portion extending through the opening, said bracket having grooves therein arranged adjacent one end thereof and extending inwardly from opposite edges of the bracket to the edges of the

opening, said grooves permitting the end portion aforesaid of the bracket to be bent laterally into clamping engagement with the member.

8. In combination, a bracket having an opening therein, a member having a portion extending into the opening, a part of the bracket adjacent the opening having a portion bowed laterally out of the plane of the bracket, and means permitting the part aforesaid of the bracket to be bent laterally to cause the outwardly bowed portion to engage the member and clamp the same to the bracket.

9. In combination, a bracket having an opening therein, a member having a portion extending into the opening, a part of the bracket adjacent the opening adapted to be bent laterally to a position adjacent the member and having an outwardly bowed portion forming a projection operable upon bending the part aforesaid to engage the member and clamp the same to the bracket.

10. In combination, a bracket having an opening therethrough intermediate the ends thereof, a member having a portion extending into the opening, said bracket having means permitting a part thereof adjacent the opening to be bent laterally to a position adjacent the member and said part having an outwardly bowed portion forming a projection operable upon bending the part to engage the member and clamp the same to the bracket.

11. In combination, a bracket having an opening therethrough intermediate the ends thereof, a member having a portion extending into the opening, said bracket having a part forming a portion of one side edge of the opening and adapted to be bent laterally for engaging the side edge portion aforesaid of the opening with the member to clamp the latter to the bracket.

12. In combination, a bracket having an opening therethrough, a member having a portion extending into the opening, a portion of said member forming one side of the opening adapted to be bent laterally to a position adjacent the member, and a projection on the portion aforesaid operable upon bending the latter to engage the member and move the same into clamping engagement with the opposite edge portions of said opening.

In testimony whereof I affix my signature.

IVAN ORNBERG. 120
